SEQUENTIAL TRIPPING MECHANISM CONTROL FOR MULTIUNIT OFFSET PRESSES

Alexander J. Albrecht, West New York, N. J., assignor to R. Hoe & Co., Inc., New York, N. Y., a corporation of New York.

Application January 27, 1948, Serial No. 4,650

3 Claims. (Cl. 101—184)

1

This invention relates to printing machines and more particularly to tripping mechanisms for rotary offset presses.

Rotary offset printing units as heretofore constructed, embody tripping mechanisms which are designed to trip the various elements of the unit on and off in a definite order and at definite times in the unit operating cycle, so that the various parts may be properly inked for applying ink to the paper and will not set off the ink or smudge the image during an operating cycle when no paper is in the unit. Such operating cycle, unless interfered with manually, has been fixed. The operating cycle, however, has been selected primarily with reference to the machine operation when printing a sheet during each operating cycle, the tripping mechanism providing for throwing the unit temporarily out of operation when a sheet is missed. A proper operating cycle for a unit when operating continuously, or substantially continuously, may not be by any means the ideal cycle for use in starting up a machine which has been out of operation for any considerable time. For example, it sometimes occurs in starting up an offset press that the paper will stick to the blanket cylinder and may tear and wrap on the blanket, necessitating suspension of printing while the paper is cleared out of the unit, and sometimes denting the blanket so as to necessitate replacement or repair and even in some cases damaging the plate. By running the plate cylinder against the blanket in advance of the time when printing by the unit is commenced, this tendency of the paper to stick to the blanket may be eliminated or very largely reduced. This effect appears to be due to the moistening of the blanket by the plate cylinder and may also be due to the working of the ink on the blanket cylinder.

It is an object of the present invention to provide for automatic premature tripping on of plate cylinders;

A further object of the invention is to provide tripping mechanisms and controls which provide for premature tripping on of plate cylinders, where necessary, without interfering with normal unit tripping cycles.

It is also an object of the invention to provide an improved unit tripping mechanism.

Still another object of the invention is to provide a trip control for multicolor offset presses including provision for sequential tripping of the units.

With these and other objects which will appear in the following description in mind, the inven-

2

tion consists in the combinations and arrangements of parts and details of construction, and the method of tripping, which will now first be fully described with reference to the accompanying drawing and will then be more particularly pointed out in the appended claims.

In the drawings:

Figure 1 is a schematic end elevation showing a blanket cylinder and associated plate cylinder together with certain tripping mechanism;

Figure 2 is a similar view showing the blanket cylinder and associated impression cylinder;

Figure 3 is a fragmentary schematic view showing the blanket and plate cylinders and certain ink motion elements associated with the latter;

Figure 4 is a view showing the tripping control mechanism of the invention, as associated with a typical unit;

20 Figure 5 is a view similar to Figure 4 but showing the parts in a different operating position;

Figure 6 is a view showing a plate cylinder and associated unit tripping mechanism embodying the invention in a modified form;

25 Figure 7 is a circuit diagram showing the manner of incorporating the mechanism of Figure 6 in a multicolor press, together with additional control elements for a multicolor offset press; and

30 Figure 8 is a circuit diagram showing still another modified form of the invention.

In Figures 1 to 5 the invention is shown as applied to an offset press having printing unit tripping mechanism generally of the type shown in Horton and Eckhard Patent No. 2,419,403, granted April 22, 1947 for Printing Machines. Only so much of the old and known tripping mechanism is shown in the drawing as is necessary for an understanding of the present invention.

40 *Unit tripping mechanism.*

In Figures 1 to 3 the plate cylinder 1, blanket cylinder 2 and the impression cylinder 3 of an offset printing unit are shown. Figure 1 shows the plate cylinder 1 and blanket cylinder 2 together with associated tripping mechanisms. Figure 2 shows the same blanket cylinder 2 and the impression cylinder 3 with other tripping mechanism, certain parts shown in Figure 1 being omitted for clearness in the drawing, and Figure 3 shows the plate cylinder 1 and blanket cylinder 2 together with part of the ink motion and tripping mechanism therefor, certain parts shown in Figures 1 and 2 being, again, omitted. In the type of unit shown, the cylinders

are separated or "tripped off" by eccentric bearings, the eccentric bearing for the impression cylinder being rotated by an arm 4 for tripping the impression cylinder 3 on and off the blanket cylinder 2, while the eccentric bearing for the plate cylinder is rotated or rocked by means of an arm 5 for tripping the plate cylinder 1 on and off the blanket cylinder 2. The tripping mechanism shown is of the type in which each rotation of the blanket cylinder causes a cycle of movement of an actuating mechanism for tripping the cylinders on and off, and the press control mechanism and a timing mechanism rotated with the blanket cylinder determine whether the actuating mechanism causes the unit to trip on or off and determine the time when this action occurs.

The impression cylinder tripping mechanism is shown in Figure 2. The actuating mechanism comprises a cam 6 rotating with the blanket cylinder and upon which rides a cam follower roller 7 at one end of an arm 8 which is pivotally mounted at 9. An operating bar 10 is pivotally connected to the arm 8 at 11 and a spring 12 serves to hold the cam follower roller 7 against the cam 6. Each rotation of the blanket cylinder, accordingly, causes a reciprocation of the bar 10. The bar 10 carries an upper abutment 13 and lower abutment 14 for engaging upper and lower studs 15 and 16 carried on a plate mounted on the impression trip shaft 17. If the bar 10 is held up abutment 13 will engage the stud 15, rocking the shaft 17 clockwise, while if the bar 10 is held down its abutment 14 will engage the lower stud 16, rocking the impression trip shaft 17 in the counterclockwise direction. Shaft 17 is connected by means of an arm 18 and link 19 with the arm 4 which rocks the eccentric bearing for the impression cylinder and the parts are so arranged that the impression cylinder will be tripped on when shaft 17 is rocked counter-clockwise, or into the position shown in the figure, and will be tripped off if the impression cylinder trip shaft is rocked clockwise.

The direction in which the bar 10 tends to rock shaft 17 is controlled by a link 20 connected to an arm of a Y-shaped member 21 pivotally mounted at 22. A second arm of member 21 terminates in a toe 23 which engages in a notch at the end of a catch 24 later described in detail. So long as the catch is in its upper position or the position of Figure 2, the Y-shaped member 21 is held from counterclockwise movement and the bar 10 is permitted to assume its lower position, or the position of the figure, so that the impression will be tripped on and remain tripped on. When the unit is to be tripped off, the catch 24 is dropped by mechanism later described, and spring 25 forces the Y-shaped member 21 counterclockwise so as to lift the rod 10 by means of the link 20. The time at which this movement occurs is controlled by means of a cam follower roller 26 carried on a third arm of the Y-shaped member 21 and cooperating with a cam 27 which rotates with the blanket cylinder. In the normal operating cycle the catch 24 will be operated while the high part of cam 27 is under the follower roller 26 and the arm 10 will thereafter be lifted at the proper point in the unit operating cycle, as determined by the contour of cam 27.

The operating mechanism for tripping the plate cylinder (Fig. 1) is generally similar to that just described and includes a plate 30 pivotally

mounted on shaft 22 and which carries a cam follower roller 32, which is urged against the cam 6 previously referred to by a spring 33. The plate 30 thus rocks back and forth during each rotation of the blanket cylinder and in so doing reciprocates a bar 34 having upper and lower abutments 35 and 36, which cooperate with upper and lower studs 37 and 38 on a plate fastened to the plate cylinder trip shaft 39. Shaft 39 is connected to arm 5 which rotates the plate cylinder eccentric bearing by means of an arm 40 and link 41.

With the parts in the position shown in Figure 1, the lower abutment 36 of the bar 34 is in position to engage the lower stud 38 for rotating the shaft 39 counterclockwise and tripping the plate cylinder on. Lifting the left hand end of this bar will bring the upper abutment 35 into position to engage stud 37 for rotating the plate cylinder trip shaft 39 clockwise and tripping the plate cylinder off. This lifting movement is accomplished through rod 45 by a bell crank 46 pivotally mounted on the shaft 9. The other arm of the bell crank is pivotally connected to a link 47 which in turn is pivotally connected to an arm 48 fixed to the impression cylinder trip shaft 17. Clockwise rotation of the impression cylinder trip shaft 17 will thus tend to rock the bell crank 46 clockwise, lifting the bar 34 for tripping off the plate cylinder.

The ink motion tripping mechanism is also operated from the impression cylinder trip shaft 17 by means of arm 50 (Figure 3) and link 51 operating on an eccentric plate 54. Rotation of this plate in one direction will bring the ink motion from rollers 52 into contact with the plate cylinder and rotation in the other direction will separate these from rollers from the plate cylinder, thus tripping off the ink motion.

A spring 53 operating on an arm fastened to the plate cylinder trip shaft 39 serves to hold this shaft in tripping on or tripping off position, as the case may be, until moved into the alternative position by operation of the bar 34 on stud 37 or 38. Similar means, not shown, and which is well understood in the art, is provided for the impression cylinder trip shaft 17.

Means may also be provided for locking one or more of the elements in tripped on or tripped off position. Such means, however, are well known in the art and are fully disclosed in the Horton and Eckhard patent above referred to and will not be described herein since they form no part of the present invention.

A number of units such as the unit shown schematically in Figures 1 to 3, may be combined into a multicolor offset printing press, suitable means for conveying sheets to be printed from one unit to the next so as to superpose the different color images in registry being provided. A variety of such means are available but it will be assumed by way of example and for simplicity that the units are incorporated in a press of the chain conveyor type such as shown and described in Huck Patent No. 2,231,914, granted February 18, 1941. In such press the successive sheets are carried through the units of the press by gripper bars. Each gripper bar is provided with an element such as a roller, indicated in dotted lines at 55 in Figure 2, which is settable at the sheet registry unit by means of detecting mechanism into either of two positions for controlling the tripping of the units. If a sheet is absent the roller 55 will be set into an upper position as in Figure 2. In this position as it approaches the

unit along the path indicated generally by the broken arrow (Fig. 2) it will engage a shoe 56 pivotally mounted at 57, rocking the shoe 56 clockwise. The clockwise rocking of shoe 56 operates through link 58 to trip the catch 24, previously referred to. As shown more clearly in Figures 4 and 5, the catch 24 is carried on a pivot 59 and has attached to it an arm 60 carrying a pin 61 which is located within a slot formed at the upper end in the link 58. The clockwise 10 rocking of shoe 56 by the gripper bar trip control roller 55 will accordingly rock the arm 60 and catch 24 counterclockwise, dropping the catch 24 below the toe 23 of the Y-shaped trip control member 21 and permitting this member to initiate the tripping off cycle of the unit under timing control by the cam 27. The catch 24 carries a projection 65 adapted to engage under a hook formed on a pivoted latch member 66. The latch member 66 is urged counterclockwise by 20 spring means (not shown) and will accordingly hold the catch 24 down even after the shoe 56 has returned to the position of Figure 2 following passage of tripping control roller 55. The toe 23 of the lower arm of the Y-shaped member 21 will accordingly be free to move when permitted to do so by cam 27. Further movement of the Y-shaped member, past the position indicated in phantom in Figure 5, will engage the curved upper end of the latch 66; thus freeing the catch 24, permitting the notch at the end thereof to catch the toe 23 upon the return movement of member 21 which is caused by cam 27 upon further rotation of the blanket cylinder.

The tripping mechanism as thus far described is well known and fully described in the Horton et al. and Huck patents referred to above, and has been described herein merely for a more complete understanding of the present invention which is concerned with provision for sequential tripping for a number of units, provision for modification of the sequential tripping cycle to trip certain plate cylinders on prematurely and with other objects which will appear from the following description.

"Normal" unit tripping cycle

In an offset press unit as just described, the printing involves the application of ink to the plate cylinder and the transfer of ink from the plate cylinder to the blanket cylinder and from the blanket cylinder to the sheet passing between the blanket cylinder and the impression cylinder. The cams 6 and 27 are so designed in relation to the positioning of the cylinders that the press elements will trip on and off at proper points. Assuming the unit to be in operation for printing upon a sheet, a printed image will be transferred from the blanket cylinder 2 to the paper at each rotation thereof. Meanwhile, the ink motion will be inking the plate cylinder in preparation for the next printing, so that a part of this ink image to be printed on the next sheet will have been transferred to the blanket cylinder in preparation for the next sheet. The tripping off of the impression will be timed so as to occur while the gap in the blanket is opposite the impression cylinder. At this time the image on the plate which is to be applied to the next sheet will have been inked so that the ink motion is tripped off at the same time as the impression. The plate is allowed to run in contact with the blanket, however, until the remainder of the ink image for the next sheet has been transferred to the blanket cylinder, at which time, while the

gap in the blanket cylinder is opposite the plate cylinder, the plate cylinder is tripped off. The blanket in a tripped off unit accordingly holds the ink to be applied to the next sheet which is accepted. When the unit is again tripped on, the blanket and impression cylinders are brought together while the gap on the blanket cylinder is opposite the impression cylinder so that the ink image on the blanket may be transferred to the sheet. Simultaneously the ink motion is tripped onto the plate cylinder for inking another image which will be applied to a second sheet. The plate cylinder, however, is not tripped onto the blanket cylinder until the gap in the blanket cylinder is opposite the plate cylinder, so that the blanket cylinder has a complete ink image applied to it for each sheet to be printed and no part of this image is inked double. These cycles of the relative movements of the cylinders and the ink motion may be characterized as the operating cycles of the unit for tripping off and tripping on.

The corresponding actions of different units may occur simultaneously or some units may be in advance of other units. If the sheet carrying devices travel at a constant speed such that the leading edge of the sheet moves at a speed equal to the peripheral speed of the impression cylinders and the length of its path of travel between units is equal to, or is an exact multiple of, an impression cylinder circumference, then all units may be in phase. Even here it will be observed that the unit cams 6 and 27 may be varied somewhat so long as the tripping on and off of the various elements occurs within the limits of the gap in the blanket cylinder. In certain cases the units may be deliberately put out of phase. For example, in a chain conveyor press a proper spacing of gripper bars and balancing of the chain may require that the path of travel of the sheet between units exceed slightly the impression cylinder circumference, so that each unit will lag behind its preceding unit by a small angle.

When the press is put into operation, starting 45 with all units tripped off, the first unit will be tripped on as a gripper bar carrying an accepted sheet approaches. The second unit will, however, remain tripped off until the sheet has passed through the first unit and the gripper bar is approaching the second unit. This will normally mean that the second unit trips on substantially one rotation of its impression cylinder, or one full cycle, later than the first unit. The present invention contemplates prematurely tripping on 50 certain plate cylinders by which is meant, for example, that the plate cylinder of the second unit may be tripped on at the same time as the plate cylinder for the first unit and one rotation of the blanket cylinder for the second unit in advance 55 of the time when it would normally be tripped on. As will be apparent from the following description, however, the invention is applicable to presses having uneven spacing between units, so that the prematurely tripped on plate cylinder 60 of a unit may not trip on at the same time as the plate cylinder of a previous unit.

While the invention is disclosed herein for definiteness as applied to an offset printing press in which the separation of the impression and blanket cylinders is accomplished by moving the impression cylinder, it will be apparent that it is also applicable to machines in which the blanket cylinder is moved away from the impression cylinder. Accordingly, when the tripping on or off 70 of the impression is referred to, it is intended to

include either of these actions. Similarly the invention has been disclosed, for definiteness, with reference to a press in which the separation of the plate cylinder and blanket cylinder is accomplished by moving the former. The invention is also applicable to offset presses in which the separation is accomplished by moving the blanket cylinder away from the plate cylinder, either of these two types of action being contemplated when reference is made to tripping on or off of the plate. The tripping on or off of the ink motion is ordinarily accomplished by moving the form rollers away from the plate cylinder but could also be accomplished by moving the plate cylinder away from the ink motion, should this become desirable. Either type of action is contemplated when reference is made to the tripping on or off of the ink motion.

Printing unit premature plate cylinder tripping mechanism

In previous devices of the character described, the link 47, which serves to control the tripping of the plate cylinder in accordance with the tripping of the impression cylinder, has been a rigid link providing a definite tripping cycle for each unit in which the order of events is not varied unless manually interfered with by the operator. According to the present invention, the link 47 is jointed to make provision for tripping the plate cylinder on in a given printing cycle of the unit, even though the impression cylinder may be tripped off, and a control mechanism for regulating the action of the links 47 in the various units is provided.

As shown most clearly in Figures 4 and 5, the link 47 comprises two sections 70 and 71 joined by a hinge 72. The hinge opens downwardly as indicated in phantom in Figure 5, but hinging in the opposite direction is prevented by a stop 73, as indicated. The section 71 of the link 47 is formed with a T-head at its right end, having an upper arm or horn 75 for engaging a stop 76 and a lower arm or horn 77, which is curved as indicated and adapted to engage a pin 78 carried on a sleeve 79. The movements of sleeve 79 are regulated by mechanism described below. If the sleeve is in a rightward position as indicated in Figure 4 and the impression is tripped off by rotation clockwise of the impression cylinder trip shaft 17 from the position of the figure to that of Figure 5, the link 47 will be forced to the left for tripping off the plate cylinder. It will be observed that the turning moment of the link section 71 about the hinge 72 which is thus created is counterclockwise. Since such counterclockwise turning is prevented by the hinge stop 73 the link 47 will act as a rigid link and will rock the bell crank 46 so as to set the plate cylinder tripping mechanism for tripping off. If, however, the sleeve 79 is moved to the left so that the pin 78 occupies the dotted line position of Figure 5, it will engage the lower arm or horn 77 of the T-head on the link section 71, rotating this section so as to break the hinge 72. With the hinge broken, as indicated in phantom in Figure 5, clockwise rotation of the impression cylinder trip shaft 17 into the position of Figure 5 will result merely in bending the link 47 about its hinge 72 so that the plate cylinder tripping mechanism will not be set to trip off. Should the impression cylinder trip shaft be already set to tripping off position and the link 47 be straight (solid line position of Figure 5), movement of the sleeve 79 to the left will, 75

through pin 78 engaging the lower horn 77, break the hinge 72, thus collapsing the link 47 sufficiently to rotate bell crank 46 counterclockwise and position the plate cylinder tripping mechanism for tripping on (phantom position of Figure 5).

Unit control mechanism for the premature plate cylinder tripping mechanism

10 Means as shown in Figures 1, 2, 4 and 5 are provided for controlling properly the movements of the sleeves 79 associated with the various units so as to obtain the desired action. These means comprise for the registering unit and each printing unit a slide bar 90, 90A, 90B etc., as the case may be, suitably carried in members attached to the frame of the machine. For understanding the action, Figures 4 and 5 may be considered as representing two successive units 15 of a multicolor press and for definiteness the first and second units thereof, Figure 5 representing the first unit, and Figure 4 the second. The bar 90A extends between the first and second units and bar 90B extends between the second and third units and this arrangement may be reduplicated indefinitely according to the number of units in the press. At the feeding end of the press, ahead of the first unit, is a similar bar 90 extending from the registering 20 mechanism to the first unit. It will be observed that all these bars are in alignment so that forcing bar 90 to the left will move all the bars 90A, 90B etc. to the left. Similarly, moving any bar associated with a unit, such as the bar 90A, to the left, will move the bars associated with later units. Each bar is urged toward the right by a spring 91, 91A etc. acting against a frame member 92, 92A etc. and against a washer 93, 93A, etc. attached to the bar. These springs serve 25 to hold any bar and all bars ahead of it in the sequence, which are not otherwise held in a leftward position, in a rightward position, or the solid line position of the figures. Each bar 90, 90A etc. carries one of the sleeves 79, each sleeve 30 79 being urged against the corresponding washer 93, 93A, etc. by a spring 94, 94A etc. acting against a washer 95, 95A etc. attached to the bar in question. Each sleeve 79 is accordingly normally held in a leftward position on its bar 90, 90A, etc., as the case may be, against the washer 93, 93A etc., but may be forced backwardly or to the right on the bar, such movement being opposed by the associated spring 94, 94A, etc. 35

40 A dog 96 pivoted at 97 (Figure 4) and urged counterclockwise by spring 98 is provided for each unit and carries a lower hook 99 in position for engaging in a notch 100 formed in the corresponding sleeve 79. The dog 96 also carries an upper hook 101 adapted for engagement by a hook 102, pivotally mounted at 103 on the stud plate of the corresponding impression cylinder trip shaft 17 and urged clockwise by a spring 104. If the impression cylinder for any unit is tripped on so that its trip shaft 17 is in the position of Figure 4, it will be observed that the corresponding sleeve 79 will be held in a rightward position by the dog 96 associated therewith, since as soon as the sleeve starts to move to the left, hook 99 will fall into notch 100. Thus, even though rod 90 and all the other rods 90A etc. may be moved to the left, the tripping cycle of the unit in question will not be affected, but the link 47 thereof will act as a rigid link. The sleeve 79 associated with other 45 50 55 60 65 70 75 80 85 90 95 100

units may be moved to the left, but the sleeve 79 associated with the unit in question will be held from such movement by the dog 96, such holding being allowed by the compression of the associated spring 94. Thus if the impression for any unit is tripped on, the tripping action of the plate cylinder for that unit will not be affected, since the sleeve 79 and pin 78 thereon are prevented from breaking the hinge of the link 47, previously referred to. If, however, the impression for a unit is tripped off as indicated in Figure 5, hook 102 engaging under hook 101 will hold up the dog 96 so that the associated sleeve 79 is free to move to the left under control of the bars 90, 90A, etc.

Operation of unit premature plate cylinder tripping mechanism

A number of actions may be obtained, depending upon the sequence of movement of the various parts just described and for a full understanding of the present invention it is necessary to review the possible actions obtainable in a given unit, depending on the position and order of movement of the parts. For this purpose the unit depicted in Figure 5 may be selected as illustrative. It may be assumed, in the first instance, that the bar 90 is in the right hand position, and that the various parts are in the full line position of the figure. It will be apparent that both the impression cylinder and the plate cylinder are set to trip off during the operating cycle of the unit in question. If the next tripping control element 55 (Figure 2) to arrive at the unit is set to trip the unit off, it will trip the catch 24, setting the unit trip control mechanism for tripping off, in advance of the time when the bars 10 and 34 make the operative parts of their strokes, so that the parts will remain in the condition of the figure. Should the control element 55 associated with the next gripper bar be set to tripping on position, it will fail to engage the shoe 56, with the result that the impression cylinder trip shaft 17 will rotate counterclockwise into the position of Figure 4, tripping on the impression cylinder, and in so doing will rotate the bell crank 46 counterclockwise for also tripping on the plate cylinder. As the impression cylinder trip shaft 17 rotates, hook 102 will disengage from hook 101, thus freeing leftward movement of the sleeve 79 associated with this unit should the bar 90 later be moved to the left.

Starting again with the parts in the full line position of Figure 5, it may be assumed that prior to the arrival of the next tripping control element 55 the bar 90 has been moved to the left (dotted line position of the figure). In this case, the sleeve 79, being free to move, will move with the bar and will break the hinge 72 of the link 47, moving this link into the phantom position of the figure and setting the plate cylinder of the unit in question to trip on. This motion of the sleeve will carry notch 100 past the hook 99 on the dog 96, thus preventing the hook 99 from falling into the notch 100 until the sleeve has been forced back to the right. The parts will remain in this position until a tripping control element 55 which is set in the tripping on position, arrives at the unit. Thereafter, at the proper time in the operation cycle of the unit, the impression cylinder will trip on, the impression cylinder trip shaft rotating counterclockwise into the position of Figure 4. This

will engage the upper arm 75 of the link section 71 against stop 76, straightening out the link 47 and forcing the sleeve 79 backward toward the position shown in full lines in Figure 4 so that the hook 99 may engage in notch 100 and hold the sleeve in its rightward position until the unit in question is again tripped off. The plate cylinder will remain tripped on. If, while the parts are in this position, the impression is again tripped off, hook 102 will not engage under hook 101 of the dog 96 by reason of the fact that the seating of the lower hook 102 in notch 100 of the sleeve lowers the hook 101 sufficiently so that hook 102 clears it.

15 The foregoing description covers the operation of the elements under various possible assumptions starting with the parts in the full line position of Figure 5 and it will be noted that so long as the associated control bar 90, 90A, etc. is in a leftward position, the plate cylinder tripping mechanism will be held to the tripping on position even though the impression is tripped off, but that as soon as the impression cylinder of the unit trips on the sleeve 79 will be held in 20 a rightward or inoperative position until such time as the control bar 90 is again moved.

Starting with the parts in the full line position of Figure 4, which corresponds to the tripping on of the unit, it will be seen that the sleeve 30 79 is at all times held in a rightward position so that the link 47 is not broken and the plate cylinder tripping cycle follows the control of the impression cylinder tripping shaft 17.

Control of premature plate cylinder tripping by the registering unit

The desired tripping cycle for the various units may be obtained by moving the bars 90, 90A, etc. in the following way: The extreme right hand end of bar 90 (Figures 1 and 2) carries a bar 110 which is pivotally attached to the bar 90 at 40 111 and the under side of which is formed with a cutout 112 engaging pin 113 at the upper end of an arm 114, which is fastened to the sheet stripping shaft 115 associated with the registering unit. This shaft carries strippers 116 and operates in a manner described more fully in the Huck patent above referred to. For purposes of the present invention, however, the precise mode 45 of operation of the stripping shaft 115 is not important as it will be apparent that any element movable from one position to another according to whether a sheet is rejected or accepted could be substituted therefor and would operate in the same way with the mechanism of the present invention. With the parts in the full line position of Figure 1, and in which the position of the shaft 115 and elements carried thereby corresponds to the position occupied when a sheet has been rejected, the spring 91 associated with bar 90 is permitted to force the bar into its rightward position in which the sleeve 79 carried thereby will not cause the tripping on 50 of the plate cylinder mechanism. The same will be true of all the other bars 90A, 90B, etc. unless held in a leftward position by other mechanism later described. If, however, a sheet is accepted, the stripping shaft 115 will rock in a counterclockwise direction into the dotted line position 55 of Figure 1, thus forcing bars 90, 90A, 90B, etc. to the left so that the premature tripping on of the plate cylinders prior to the time when the impression cylinders are tripped on is obtained.

70 75 It may be assumed, in the first instance, that

the press is out of operation, which implies that empty gripper bars have passed through all units and have tripped these units off. The mechanism at each unit will be in the full line position of Figure 5, the hooks 101 and 102 at each unit having been caused to engage, as shown by reason of the rightward or clockwise movement of the arm 114 and hence of the bars 90, 90A etc. As soon as a sheet is accepted, the arm 114 will swing counterclockwise into the dotted line position of Figure 1, and will hold all the bars 90, 90A, (Figure 5) and 90B (Figure 4), in their leftward positions. All sleeves 79 will also move to the left, breaking the links 47 as indicated in phantom in Figure 5. All of the plate cylinders will now trip on under control of the cams 6. When the gripper carrying the properly registered sheet arrives at the first unit, the impression cylinder for that unit trips on by reason of the fact that the control element 55 associated with this gripper bar fails to operate the shoe 56. The impression cylinder of each succeeding unit likewise trips on one cycle later than the immediately preceding unit. The result is that the first unit in line will have its plate cylinder tripped on one cycle early or before the cycle in which its impression cylinder is tripped on, while the second unit in line will have its plate cylinder tripped on two cycles early, and the plate cylinder of each succeeding unit will be tripped on prematurely during an additional cycle. If it is desired to silence the premature tripping control from the registering unit, this may be done by means of a hand lever 120. Swinging this lever from the full line position of Figures 1 and 2 into the dotted line position of Figure 2 lifts the bar 110 into the dotted line position of the latter Figure, so that the bar 110 is lifted clear of the pin 113 and the spring 94 associated with rod 90 is permitted to hold it in its rightward position.

In some multicolor rotary offset machines, it is found desirable to permit the machine to run following the rejection of a sheet, the successive units tripping off sequentially as the empty gripper bar corresponding to the rejected sheet passes through them, then tripping on again as soon as a gripper bar containing an accepted sheet approaches. The invention, while applicable to such machines, is shown as applied to a machine in which once a sheet is rejected, all succeeding sheets are rejected until the mechanism is reset. This action is provided for by a latch 121 cooperating with an inner pin 122 on the arm 114 previously referred to. Whenever the stripper shaft 115 rotates clockwise into the full line position of Figures 1 and 2, the pin 122 will be caught by the latch 121, holding the shaft 115 and parts carried thereby in this position until the latch 121 is lifted manually, again permitting the shaft to move counterclockwise into the position for accepting sheets. In such a machine, when a sheet is rejected, the first unit will trip off and remain tripped off and will be followed in order by the second and succeeding units, so that the units of the press will progressively go out of operation and remain out of operation until the latch 121 is lifted by the operator. In this type of machine, as soon as a sheet has been rejected, all the bars 90, 90A etc. will move to the right, and will remain to the right, as also will the sleeves carried thereby so that as each impression cylinder trip shaft 17 rotates clockwise into the tripping off position, the hook 102 associated therewith will engage under and hold the hook 101 as indicated in Figure 5.

Control of the premature plate cylinder tripping by a printing unit

Means is also provided at each printing unit 5 for controlling the operating bars 90A, 90B etc., as the case may be, for all later units. This mechanism comprises for each unit a bar 125 having a cutout 126 adapted to fit over a pin 127 carried on the impression trip shaft stud plate. The leftward end of this bar is pivotally connected at 128 to the upper end of a lever 129 which is pivotally mounted at 130 and the lower end of which is formed as a fork surrounding a pin 131 on the operating rod for the next unit. In the case of the unit shown in Figure 4, this is the operating rod 90B, while in the unit shown in Figure 5, it is the rod 90A.

The bar 125 may be set into an operating or non-operating position by means of handle 132 pivotally mounted at 133. With this handle in the off or full line position of Figure 4, bar 125 will be held in such a position that its cutout 126 cannot engage pin 127 and accordingly bar 125 will move idly (full and phantom lines in Figure 5) and the rod 90B may be moved back and forth but will not affect the operation of the unit in any way. If the handle 132 is moved into the on position or phantom position of Figure 4, bar 125 will assume the phantom position of that figure resting on pin 127 within the cutout 126. The associated impression cylinder trip shaft 17, if rotated to the tripping on position or position of Figure 4 with pin 127 engaging against one end wall of the cutout 126 will pull the bar 125 to the right, thus rocking lever 129 clockwise into the phantom position of Figure 4 and forcing rod 90B and any later rods 90C etc. to the left.

By suitably setting the handle 120 at the registering unit and the various handles 132 at the printing units, premature tripping of the plate cylinders may be varied as desired.

With handle 120 at the registering unit set in its lower or "on" position and with the handles 132 at the printing units all set in their upper or off positions, the premature tripping of the units will be controlled by the registering unit as previously described.

If handle 120 and all the handles 132 are set in the "off" position, there will be no premature tripping of any plate cylinders and the operation of the press units will be according to the normal tripping on and tripping off cycles as disclosed in the Horton et al. and Huck patents above referred to.

If handle 132 for the first unit is set in the "on" position, while handle 120 and the remaining handles 132 are set in the "off" position, the bar 90 will remain in its rightward position at all times and the tripping cycle of the first unit will be normal. As soon as the first unit impression trips on, the bar 90A will move to the left, also moving bars 90B etc. The plate cylinders of the second and later units will now trip on. Thus, the second unit plate cylinder will trip on one cycle early, the third unit two cycles early, etc.

Similarly, handle 132 in the second unit may be set on and the handle 120 and all other handles 132 set off, in which case the tripping on of the first and second units will be normal while the plate cylinders of later units will be tripped on prematurely.

Emergency trip

Means is provided for tripping off all units, 75 as may be required in the case of emergency.

This means comprises a rod 140 slidably mounted and extending the length of the machine. The rod is urged to the left by means of springs 141 but may be moved toward the right by a hand lever 142 (Figure 1), on the register unit. The rod carries, for each printing unit, a stud 143 (Figure 4), which is received within a fork 144 formed on arm 60 attached to the trip control catch 24 of the unit. Fork 144 is wide enough so as not to interfere with the normal operation of the machine. However, when the rod 140 moves to the right, the pins 143, through forks 144, will rotate the catches 24 counterclockwise, dropping them so as to set all units to trip off during the same cycle. Hand lever 142 may thus be used for emergency tripping off of all units.

Silencing mechanism for the premature trip controls

Means is also provided for silencing the premature tripping mechanism for any unit, whenever desired, and comprises an arm 150 (Figure 4), which is loose on the shaft 151 and has a fork at its upper end engaging around a pin 152 carried on the sleeve 79. The arm 150 normally moves idly back and forth (full and phantom lines in Figure 5) but may be locked in a clockwise position (Figure 4) by turning a handle 153 from the full line position of Figure 4 to the phantom position of that figure. It will be apparent that this will hold the associated sleeve 79 in a rightward position, thus silencing the premature plate cylinder tripping mechanism of the unit in question.

By suitably combining the settings of handles 153 and the setting of handles 120 and 132, additional combinations of normal tripping cycles and premature plate cylinder trippings for the various units may be obtained. For example, if the handle 120 is set on, all handles 132 are set off and the premature plate cylinder tripping mechanism for the second unit is silenced by means of its handle 153, the second unit of the press will follow its normal tripping cycle and its plate cylinder will not trip on prematurely. The plate cylinder of the first unit will, however, trip on one cycle in advance, while that of the third unit will trip on three cycles early, etc.

While it will ordinarily not be necessary to provide for such action, the silencing by handle 153 may be utilized to provide for premature tripping on of the plate cylinder of one unit and not of a later unit.

Reverse trip off mechanism

It is desirable to trip off all units automatically when the press drive is reversed. For this purpose a pawl 160 (Figure 4) mounted on a pivot 161 which rotates with the blanket cylinder 2, is provided. The pawl is urged clockwise by a spring 162 which normally holds it against a stop 163. A bell crank 164 mounted on a stationary pivot 165 carries a roller 166 in position for cooperation with the pawl 160 and the other arm of the bell crank is connected through a link 167 and lost motion connection to an arm 168 which is fastened to the latch 24. So long as the press is operated in the forward direction, so that the blanket cylinder is rotated in the direction of the arrow of Figure 4, the pawl 160 will be pressed idly inward each time it passes the roller 166 and no movement of latch 24 will be produced. If, however, the unit is reversed, pawl 160 will engage roller 166, rotating the bell crank 164 clockwise and thus through

the link 167 dropping the catch 24 so as to set the unit for tripping off. By this means provision is made for tripping off all units during the same cycle whenever the press drive is reversed.

5 *The modified arrangement of Figures 6 and 7*

In the embodiment of Figures 6 and 7, the unit tripping mechanism is modified and an electric control circuit is provided which may be operated by a rotary sequential trip controller such as shown in the Horton and Eckhard Patent No. 2,419,403. Figure 6 shows the blanket cylinder 2, it being understood that the plate cylinder, impression cylinder and other mechanism apart from the tripping controls may be the same as in the unit described in connection with Figures 1 to 5. Parts in Figure 6 which correspond to those already described in connection with Figures 1 to 5 are identified by the same reference numerals and further description thereof is unnecessary. It will be observed that the impression cylinder trip shaft and the control of the tripping thereof by the cams 6 and 27 are the same as previously discussed, the impression cylinder tripping being controlled by a bell crank catch 200 pivoted at 201 and of somewhat different form than the catch 24 previously discussed. It will be understood that the mechanism operated by shaft 17 for tripping off the impression cylinder and for tripping off the ink motion may be the same as that shown in Figures 1 to 5.

The plate cylinder trip shaft 39 and the parts operated thereby are the same as those in the embodiment of Figures 1 to 5, and a bar 202 having upper and lower abutments 203 and 204 operates in the same way as the bar 34 previously discussed. The raising and lowering of this bar when tripping off and tripping on is, however, accomplished in a different manner, a separate control member not operated by the impression cylinder trip shaft being provided. This member is a Y-shaped member 205 similar to the Y-shaped member 21 which controls the impression cylinder tripping mechanism and is rotatable on the shaft 9, being urged clockwise so as to bring its cam follower roller against the cam 27. Its lower arm or leg terminates in a toe 206 engaging in a notch at the end of one arm of a bell crank catch 207 which is pivotally mounted at 208.

The impression cylinder latch 200 is operated by means of a solenoid 210. If this solenoid is energized the latch 200 will be rotated counterclockwise so that the toe 23 on the lower arm of 55 the Y-shaped impression trip control member 21 is released and this member is free to rotate counterclockwise under control of the cam 27 so as to cause the impression cylinder to trip off. The latch 200 is formed with a projection or hook 211 facing the toe 23 which serves to prevent accidental operation of the impression cylinder tripping mechanism at an improper point in the cycle. If the cam 27 is in the position of Figure 4, spring 25 will urge the toe 23 under the hook 211, thus preventing solenoid 210 from rotating the catch 200. This prevents damage to the operating parts which might result if the cam follower roller 26 of the Y-shaped member were slammed down against the low dwell of cam 27 by the spring 25. If, however, the high dwell of cam 27 is under the follower roller on arm 26, the Y-shaped member will be held in a slightly more clockwise position than that shown, 60 permitting solenoid 210 to operate the catch 200, 65 70 75

thus causing the tripping off of the impression at the proper time.

The solenoid 229 operates the plate cylinder trip control latch 207 in a similar way. The latch 207 has a hook 221 similar to the hook 211 of the latch 200 and is also provided with a projection 222 for engagement under a catch 223. Projection 222 and catch 223 operate in a similar manner to projection 65 and catch 66 on the latch 24 previously discussed in connection with Figures 1 to 3, so as to permit the plate cylinder tripping mechanism to operate under control of the cam 27 even though solenoid 229 may have been previously deenergized.

The plate cylinder trip shaft 39 carries an abutment 230 for operating a switch C while the impression cylinder trip shaft 17 carries an abutment 228 for operating a switch D, these switches being utilized as shown in the circuit of Figure 7 for controlling the tripping action. In the circuit diagram of Figure 7, the switches C and D in the various units are identified as switches C², C³ and D², D³, according to the units on which they are mounted.

Figure 7 indicates the controls for three units in a multicolor offset press, controls for each unit being enclosed in rectangles marked out in phantom lines and the successive units being identified by numerals I, II and III. A fourth unit IV and any number of succeeding units desired may be added in a manner which will be apparent when the circuit has been explained.

The solenoids 210 of the units are controlled by relays A', A² etc. One end of the winding of each solenoid 210 is connected to power line L' and the energizing of the associated relay A', A² etc. will close its contacts, establishing connection of the other end of the solenoid winding to power line L², thus energizing the associated impression trip solenoid 210.

The plate cylinder trip solenoids 220 are controlled in a similar way by relays B', B² etc.

Each of relays A', etc., B., etc., has one end of its winding connected to power line L'. The other ends of the windings of relays A' etc. are connected to three-way switches 231, one switch being provided for each unit and the windings of relays B' etc. are similarly connected to switches 232. With the switches 231 and 232 set as indicated in the figure, automatic control circuits as hereinabove described are established. Each of the switches 231 and 232 has an upper dead contact so that setting the switch on its upper contact disconnects the associated relay A', etc. or B' etc. and the plate cylinder or impression cylinder controlled thereby will remain tripped on, unless tripped off by emergency or reverse tripping circuits, later described, which trip off all units. Setting a switch 231 or 232 in its lowermost position connects the winding of the associated relay A' etc. or B' etc. directly across lines L' and L², so that the plate or impression cylinder controlled thereby will trip off and remain tripped off until the setting of the switch in question is changed.

Assuming the switches 231 and 232 to be set on their middle contacts, as shown in Figure 7, a connection for each unit is established to a rotary controller of the type shown in the Horton and Eckhard patent. This controller comprises a rotary member running in synchronism with the printing press and carrying a number of switch operating elements 235, which cooperate with sequential trip control switches S', S², S³ and S⁴. If a sheet is rejected an appropriate element

235 will be set in an outward position so as to operate the switches S' etc. as it passes by them. When sheets are accepted, however, the elements 235 will be set in an inward position, or non-operating position. It will be understood that the elements 235 are operated as in the Horton and Eckhard patent so that the time of passage of an element 235 past the switches S' etc. is synchronized with the movement of a gripper bar through the machine for successively tripping off the units if the gripper bar carries no sheet or for successively tripping on the units if the gripper bar carries a sheet. One side of each of the switches S' etc. is connected to a line 236 leading to the power line L². The other side of switch S' is connected to a line 237 to which the center contacts of switches 231 and 232 of the first unit are connected. Line 237 is also connected to the lowermost contacts of selector switches E², E³, E⁴ etc.

The center contact of switch 231, second unit, is similarly connected to a line 238, which leads to the switch S². The center contact of switch 232 of the second unit is not, however, connected directly to this line but a connection path thereto may be established through line 239 and switches C² and D², provided these switches are in the position of the figure. Line 238 continues, and is connected to the second lowest contact of selector switches E², E³ and E⁴.

Similarly, the center contact of switch 231 of the third unit is connected to a line 240 which leads to switch S³ of the rotary controller. This line is connected to the third contact of switch E³ and E⁴ as indicated and connection to line 240 of the center contact of the switch 232 of the third unit may be established through a line 241 and switches C³ and D³, provided these switches are in the position on the figure.

The switches E², E³, etc. are utilized for selecting the unit which is to control the preliminary tripping of later units. With these switches set as shown in the figure, such control will be exercised by the first unit and the operation with the switches thus set will now be described. The switches C², C³, etc. associated with the plate cylinder trip shafts of the units will occupy the position shown in Figure 7 when the plate cylinders are tripped on, and these switches will make contact in their lower position when the plate cylinders are tripped off so as to connect lines 239 and 241 through lines 250 and 251 with the switches E², E³. The switches D², D³ etc. will be closed, as shown in the figure, when the corresponding impression cylinders are tripped on but will be open when their associated impression cylinder trip shafts 17 are turned clockwise into their tripped off positions.

It will be assumed, in the first instance, that the press is out of operation and that all switch operating elements 235 of the rotary controller are set to trip off by closing the switches S' etc. as they pass by them, and that all plate and impression cylinders are tripped off. Switches D², D³ etc. will then be open, while switches C², C³ etc. will be in their lower positions connecting lines 239 and 241 to switches E², E³ etc. Under these conditions the impression cylinder solenoid control relays A', A² and A³ will be controlled by the respective switches S', S² and S³ by virtue of the connections established through lines 237, 238 and 240. However, the plate cylinder solenoid control relays B', B² and B³ will all be controlled from line 237 leading to switch S', the connection for relay B² being established through

line 239, switch C², line 250 and switch E², and the connection for relay B³ being established through line 241, switch C³, line 251 and switch E³.

When a switch control element 235 which has been set in non-operating position by reason of the acceptance of a sheet passes switch S', switch S' will remain open so that the plate and impression cylinders of the first unit will be set to trip on at the proper point in the rotation cycle of that unit, by virtue of relays A' and B' not being energized. Similarly, the plate cylinders of units II and III will trip on prematurely during the same cycle as the plate cylinder of the first unit trips on. The impression cylinders for the second and third units will, however, remain tripped off by reason of the fact that relays A² and A³ will be energized by switch control elements 235, which are still in the sheet rejecting and switch operating position, closing switches S² and S³. During the same cycle the tripping on of the plate cylinder of the second unit moves switch C² into the position of Figure 7. Switch D² being still open, the plate cylinder of the second unit remains tripped off. If the next sheet is accepted the next switch control element 235 in order on the rotary controller will also be set in non-operating position. When this element reaches switch S', switch S' will not be closed so that unit number I remains tripped on. At the same time the immediately preceding switch control element 235 will be opposite switch S² so that this switch also will remain open and the impression cylinder for the second unit will trip on while the plate cylinder will remain tripped on. It will be recalled that during the first cycle discussed the plate cylinders for all units were tripped on so that switch C³ and any later corresponding switches were moved to the upper position, or position of Figure 7, at about the same time as switch C². Switch D² and any later similar switches, however, remained open so that tripping off of the plate cylinders for the second and any later units by rotary controller switch S² and any later rotary controller switches was prevented. The tripping on of the second unit impression during the second cycle will now, however, have restored switch D² to the position of the figure so that the second unit is under full control by rotary controller switch S². However, the switch control element 235 to reach switch S² during the third cycle of operations will be the second such element which was set to non-operating position so that switch S² will remain open with the result that the plate and impression of the second unit remain tripped on. By the means just discussed, the plate cylinder of the second unit is tripped on prematurely by one operating cycle of that unit while the plate cylinder of the third unit is tripped on prematurely by two operating cycles, etc. While the elements of a fourth unit are not shown in Figure 7, a line 242 leading thereto from switch S⁴ and a selector switch E⁴ are shown, so that the manner of adding a fourth or any desired number of units will be obvious.

If it is desired to control the premature tripping by a later unit, the switches E², E³ etc. are reset. For example, setting each of these switches up one contact will connect the lines 250 and 251 and any further similar lines of later units to line 238 leading to rotary controller switch S². The result of this will be that the first unit will trip on under control of switch S' as before. During this operating cycle the

later units will remain tripped off by reason of the fact that relays A² and A³ will be energized through lines 238 and 240 while relays B² and B³ will both be energized from line 238 and switch S² through switches E² and C², and E³ and C³, respectively. The tripping on of the second unit will reset switches C² and D² into the position of Figure 7, so that the third unit plate will trip on prematurely but the third unit impression will not trip on until the non-operating switch control element 235 reaches switch S³, at which time the third unit will be set to trip on. Any later unit plate cylinder will trip on prematurely during the same cycle as the third unit plate cylinder.

Setting the switches E², E³ etc. one contact higher will result in the first, second and third units tripping on normally while the fourth and any later units will trip on prematurely as described.

Once the press is in operation, all switches C² etc. and D² etc. will be in the position of the figure, so that each unit is under control of its own rotary controller switch. As soon as a sheet is rejected, and a switch controller element 235 is therefore set in switch operating position, the successive units will trip off one after another as this switch controller element reaches the corresponding switches S' etc. This action occurs in the following way: During the first cycle switch S' closes, energizing relays A' and B' and setting the first unit to trip off. During the next cycle this trip control element operates switch S², opening switch D² and setting switch C² on the lower contact. A similar action occurs for the third and later units in sequence. This action is not affected by the setting of the switches E², E³ etc., for premature plate cylinder tripping under control of the first, second or later units, since the impression and plate for each unit will always be tripped off by the rotary controller switch associated with that unit.

Means is provided for tripping off all units simultaneously under certain conditions, and is also shown in Figure 7. This means comprises a relay R', one end of the winding of which is connected through a line 260 to the power line L', while the other end of the winding is connected through lines 261 and 262 to a contact of the relay R². An alternate connection path to another contact of relay R² may be established through pushbutton switches P' and P² and line 263. A maintaining circuit for relay R' is provided, through line 264, a pair of the relay contacts, and line 265 connecting through pushbutton P² to the line 263 previously referred to. The relay R² is a reversing relay for the press and is controlled by reverse pushbutton P³. If the reverse button P³ is not pressed for reversing the printing press, connection between line 263 and line L² is established through contacts of the relay R² and lines 266 and 238. Pressing the emergency trip button P' will thus energize relay R' through line 261, pushbuttons P' and P² and lines 263, 266 and 236 leading to power line L². The relay once energized will remain energized by reason of the closing of its contacts connecting the maintaining circuit lines 264 and 265, until the release button P² is pushed to open the circuit. The energizing of relay R' connects each of lines 270, 271, 272, 273, 274 and 275 with line 265 and thus through the circuit previously traced to power line L², so that all of the relays A', etc. and B', etc. are energized, tripping off all im-

pression and plate cylinders. Pushing the emergency trip button release P^2 breaks the maintaining circuit of relay R' , thus deenergizing the relays A' , B' etc. and restoring the control circuit as previously described. The circuit also provides for automatic tripping off of all impression and plate cylinders upon reversal of the press. Pushing the reverse button P^3 will energize the relay R^2 , breaking the connection between lines 263 and 266, but establishing connection between lines 266 and line 262 which bypasses the push buttons P' and P^2 so that when the reversing relay R^2 is energized all units will be tripped off.

Comparison of the embodiment of Figures 1 to 5 with that of Figures 6 and 7

While the embodiment of Figures 6 and 7 discloses the operation of the trip control mechanism by a rotary controller, it will be apparent that the same circuits can be utilized in a press utilizing control by means of the gripper bars or other sheet carrying elements. All that would be necessary to effect this modification would be to substitute for the rotary controller switches S' , etc., similar switches operated by shoes 56 at the various units as described in connection with the embodiment of Figures 1 to 5, such shoes being suitably located for the proper timing of the action.

It will also be observed that most of the mechanism of Figures 1 to 5 is replaced by mechanism producing similar results in Figures 6 and 7. For example, the selector switches E^2 , E^3 etc. perform similar functions to the handles 120 and 132 by which the point in the line of units at which the premature tripping will commence is determined. The switches 231 and 232 provide for manually setting on a given plate or impression cylinder in either tripped on or tripped off relation regardless of the operation of the remainder of the press and thus perform the functions of the manually operated mechanical elements heretofore provided in a machine of the type such as shown in Figures 1 to 5. Relay R' and pushbutton P' perform a similar function to the rod 140 and handle 142. A quicker tripping off action in case of emergency may, however, be obtained, since in the embodiment of Figures 6 and 7 it is possible for the plate cylinder to trip off in advance of the impression cylinder, while in the embodiment of previous figures, the tripping off of the plate cylinder will always follow the tripping off of the impression cylinder and must wait until this has occurred. The pushbutton P^3 , reversing relay R^2 and relay R' perform similar functions to the reversing trip off pawl 160 and associated apparatus. Here again, however, the actual tripping off of the units may occur sooner for the same reasons as pointed out in connection with the emergency tripping off. Provision for silencing the preliminary plate cylinder tripping mechanism for any unit is made by means of the switch E^2 etc., for setting any one of these on its uppermost contact subjects the corresponding unit to control only by its own rotary controller S_2 etc. as the case may be. In this way, provision is made for a similar action to that obtained by means of silencing handles 153.

The embodiment of Figures 6 and 7 possesses the advantage of flexibility and simplicity which are often inherent in electrical control systems as distinguished from mechanical systems. For example, a unit equipped with the double solenoid control of Figure 6 may be adapted for different normal tripping cycles by merely rewiring its control circuits. Such a unit is capable of

tripping a plate cylinder on in advance of the impression cylinder, in which case the ink impression in a tripped off unit will be held upon the cylinder instead of the blanket cylinder, this arrangement being advantageous in certain applications.

The embodiment of Figure 8

Still another form of the invention is shown in the circuit diagram of Figure 8. In the form of Figures 1 to 5 inclusive, the sequential tripping of the units was controlled by means associated with the sheet carrying means. In the form shown in Figures 6 and 7 sequential trip controlling was accomplished by means of a rotary controller driven in synchronism with the press. In the form of Figure 8 the sequential tripping of the units is controlled by the units themselves, the tripping off of one unit setting the following unit to trip off, and so on.

The mechanical elements of the tripping mechanism for the units may be the same as in the embodiment of Figures 6 and 7 and may be controlled by similar solenoids and relays. In the circuit of Figure 8, accordingly, the same solenoids 210 and 220 and control relays A^1 , A^2 and B^1 , B^2 are indicated. The arrangements shown for emergency tripping off of the units are likewise the same, as also are the control switches 231 and 232.

Switches operated by the plate cylinder and impression cylinder trip shafts in a manner similar to the switches C^2 etc. and D^2 etc. are again provided. A switch d' operated by the impression cylinder trip shaft 17 of the first unit is provided as well as a switch d^2 and switch c^2 operated respectively by the impression and plate cylinder trip shaft of the second unit.

The sequential tripping according to whether sheets are accepted or rejected in the registering unit is conveniently initiated by the stripping shaft 115 of the registering unit, previously described in connection with Figures 1 to 5, the stripper element 116 being utilized to operate a control switch 300. If a sheet is accepted, so that the stripper 116 is in its counterclockwise position, switch 300 will be opened, while if the stripper 116 is in its clockwise position for rejection of the sheet, the switch 300 will be closed.

Switch 300 is connected to switches 231 and 232 of the first unit for controlling the relays A' and B' . Accordingly closing of switch 300 when a sheet is rejected sets the first unit to trip off, while opening switch 300 sets this unit to trip on.

Assuming both units shown in Figure 8 to be tripped on, which is a condition corresponding to the switch positions shown, the rejection of a sheet will close switch 300, which sets the first unit to trip off. When the impression cylinder of this unit trips off, switch d' shifts to its lower position, connecting line 303 leading to the second unit to power line L^2 through a line 302. This sets the second unit to trip off, relay A^2 being energized through a line 304, and relay B^2 being energized through switches d^2 , c^2 and a line 305. When the second unit impression trips off, switch d^2 shifts to its lower position energizing a line 309 leading to the third unit, if any, for setting each unit, in turn, to trip off. Switch c^2 also shifts to its lower position, thus connecting relay B^2 to selector switch E^2 .

Assuming both units to be tripped off, with switches d' , d^2 and c^2 in their lower positions, and that a sheet is accepted so that switch 300 opens, relays A' and B' will be deenergized, set-

ting the first unit to trip on. At the same time, plate cylinder trip relay B^2 , which is connected to line 301 through switches c^2 and E^2 will also be deenergized, setting the plate cylinder tripping mechanism of the first unit to trip on during the same cycle. The second unit impression will remain set for tripping off during this cycle, since a connection for energizing relay A^2 is maintained through switch d' until the impression of the first unit trips on, restoring the switch d' to the position of the figure and thus deenergizing relay A^2 to set the impression trip mechanism of the second unit to trip on during the next cycle. At the time when the plate cylinder of the second unit tripped on, switch c^2 returned to the position of the figure, but no connection was established for energizing relay B^2 by reason of the switch d^2 being still in its lower position. As the impression for the second unit trips on, switch d^2 returns to the position of the figure, but line 303 is now dead, by reason of the previous return of switch d' .

If selector switch E^2 is set on the upper contact, and it be assumed that both units are tripped off, the action upon acceptance of a sheet will be the same as before described, except that relay B^2 , being controlled from line 307 will be energized during the first cycle, through line 392, switch d' , line 303, line 307, switches E^2 , c^2 and line 305. The plate cylinder for the second unit will, therefore, not trip on prematurely.

The manner of adding units will be apparent from Figure 8 and the foregoing description, each added unit having a selector switch E^3 etc. and switches c^3 , d^3 etc.

What is claimed is:

1. In a multicolor offset press having a plurality of printing units for printing in predetermined sequence on a sheet, and each of which comprises plate, blanket and impression cylinders, an ink motion and a unit tripping mechanism for tripping the plate, impression and ink motion off in predetermined order and in timed relation to the rotation of the impression cylinder, and for tripping the plate, impression and ink motion on in the same predetermined order and timed relation, and in combination, a sequential trip control for operating the unit tripping mechanisms of the units in the said predetermined sequence, and further plate trip control means operated by the sequential trip control for tripping on the plate of a unit during a rotation of the impression cylinder preceding the rotation in which the first said unit tripping mechanism is operated by the sequential trip control in the said predetermined sequence to trip on the impression and ink motion.

2. In a multicolor offset press having a plurality of printing units for printing in predetermined sequence on a sheet, and each of which comprises plate, blanket and impression cylinders, an ink motion and a unit tripping mechanism for tripping the plate, impression and ink motion off in predetermined order and in timed relation to the rotation of the impression cylinder, and for tripping the plate, impression and ink motion on in the same predetermined order and timed relation, and in combination, a sequential trip control for operating the unit tripping mechanisms of the units in the said predetermined

sequence, and further plate trip control means for a group of successive units, and operated by the sequential trip control, for tripping on the plate of the first unit of the group during a rotation of its impression cylinder preceding the rotation in which the first said unit tripping mechanism is operated by the sequential trip control in the said predetermined sequence, to trip on its impression and ink motion, and for tripping on the plate of each succeeding unit of the group in advance of its impression and ink mechanism by one more rotation of its impression cylinder than in the case of the preceding unit.

3. The combination according to claim 2, in which the said further plate trip control means is adjustable to select any of a plurality of groups of adjacent units for advance tripping on of their plates.

4. The combination according to claim 3, in which means is provided for silencing the further plate trip control means for a selected unit.

5. In a multicolor offset press having a plurality of printing units for printing in predetermined sequence on a sheet, and each of which comprises plate, blanket and impression cylinders, an ink motion and a unit tripping mechanism for tripping the plate, impression and ink motion off in predetermined order and in timed relation to the rotation of the impression cylinder, and for tripping the plate, impression and ink motion on in the same predetermined order and timed relation, and in combination, a sequential trip control for operating the unit tripping mechanisms of the units in the said predetermined sequence, and further plate trip control means comprising means, controlled by the tripping on of a unit by the said sequential trip control, for tripping on the plate of a succeeding unit at substantially the same time as the plate of the first said unit.

6. The combination according to claim 5, in which the said further plate trip control means is provided for a group of succeeding units and comprises means for tripping on the plates of all said units at substantially the same time.

7. The combination according to claim 6, in which the said further plate trip control means is adjustable to select any of a plurality of groups of adjacent units for tripping on their plates at substantially the same time.

8. The combination according to claim 7, in which means is provided for silencing the further plate trip control means for a selected unit.

ALEXANDER J. ALBRECHT.
